(57) **CLAIM**

The ornamental design for a socket, as shown and described.

DESCRIPTION

FIG. 1 is a front elevation view of a socket, showing my new design;

FIG. 2 is a rear elevation view thereof;

FIG. 3 is a left side elevation view thereof;

FIG. 4 is a right side elevation view thereof;

FIG. 5 is a top plan view thereof;

FIG. 6 is a bottom plan view thereof;

FIG. 7 is a front bottom perspective view thereof;

FIG. 8 is a front, left-side, top perspective view thereof;

FIG. 9 is a front, right-side, top perspective view thereof;

FIG. 10 is a rear, left-side, bottom perspective view of thereof; and,

FIG. 11 is a rear right-side, bottom perspective view thereof. The broken lines in the drawings are for the purpose of illustrating portions of the socket that form no part of the claimed design.

1 Claim, 11 Drawing Sheets
